AIR CONTROLLED THROTTLE

Joel B. Fulton, High Point, N. C., assignor to
R. L. Brinson Company, trading as Transport
Apparatus and Device Company, High Point,
N. C.

Application May 28, 1946, Serial No. 672,736

1 Claim. (Cl. 230—3)

1 My invention relates to an air-controlled throttle, and it is an object of the same to provide quick-acting sensitive means for reducing the speed of an air compressor driving engine when the pressure in the air storage tank rises to a predetermined limit, combined with quick-acting sensitive means for speeding up said engine when the pressure falls below a predetermined limit, the hook-up being such as to combine quick speed-up and slow-down action of the compressor synchronized with quick action of the throttle control so that the engine slows down and speeds up in synchronism with the quick changes of operation of the compressor.

Another object is to provide simple and inexpensive automatic means for effectively controlling the action of a compressor and its driving means so as to maintain substantially a predetermined air pressure in a reservoir.

Referring to the drawings, which are made a part of this application and in which similar reference characters indicate similar parts:

Fig. 1 is a side elevation of my device, in the embodiment thereof which is at present preferred;

Fig. 2 is a detail of throttle valve means.

In the drawings, reference character 10 indicates an air storage tank, connected by an inlet pipe 11 to a compressor 12 that may be of any conventional or preferred type, it being here shown as consisting of a model A Ford automobile engine converted into an air compressor by fitting it with a special cylinder head serving to pump air into pipe 11, and being provided with unloader valves 13, 13, connected by a pipe 14 to an air governor 15, here shown as being of a well-known type made by the Westinghouse Company and used on motor trucks and elsewhere.

The compressor is driven by a Diesel engine 16 through a shaft 17 which is partially concealed by a member 18 of the channel iron framework that supports the mechanism on posts 19 fixed in a floor of concrete or the like. The engine is of conventional construction except as herein specified, and it has a throttle arm 20. A coil spring 21 tends to open the throttle to about two-thirds of its full capacity. A rod 22 is connected at one end to the throttle arm, said arm having several holes by means of which the rod may be connected thereto at various points along the arm to vary the action of the rod and the rod-operating means on the throttle. The rod is connected at its left-hand end to a diaphragm located in an air pressure operated central device 23, here shown as consisting of a five-inch brake wheel chamber, the arrangement being such that when air under

sufficient pressure is supplied to the chamber through pipe 24 the throttle valve will be pushed counter-clockwise toward closed position.

A pipe 25 leads from the tank 10 to an air filter 26, connected by a pipe 27 to the air governor 15. An outlet pipe 28 leads from the governor 15 to pipe 14 and also to a pipe 29 connected through a quick release valve 29 to pipe 24. The main outlet from tank 10 is shown at 30.

10 In the operation of the device, the compressor is driven by the engine to force air into tank 10. The speed of the engine may normally be about 600-700 R. P. M. Now if the pressure in the tank exceeds a predetermined limit, e. g. about one hundred pounds per square inch, such pressure will act through parts 25, 26, 27, 15 and 14 to unload valves 13, first unseating a valve in governor 15, such unseating permitting the air under pressure to pass into pipe 14 and thus unseating 15 the unloader valves, so that the air from the compressor passes to outer atmosphere instead of to tank 10 and the engine runs free. Under such circumstances, the speed of the engine increases 20 suddenly to as much as 1600 or 1800 R. P. M. unless the throttle is closed to idling speed, with 25 obvious deleterious effects. To obviate damage, an attendant has been stationed at the machine to close the throttle and to reopen it at proper 30 times, and one object of the invention is to save the manpower thus wastefully employed.

To this end, the pipe 28 is connected to receive compressed air from governor 15 at the same time as pipe 14, and to conduct it through valve 29 and pipe 24 to the chamber 23, where it acts on rod 35 22 to push the throttle toward closed position and so reduces the speed of the Diesel engine.

When the pressure in tank 10 falls to a predetermined limit, e. g., to ninety pounds per square inch, air bleeds through the air governor and 40 relieves the pressure on the unloader valves, permitting them to return to active position, whereupon air is again forced into tank 10 by the compressor and the engine, which have merely been running idly.

45 At the same time, the air pressure in the brake chamber is relieved and the connecting rod 22 moves to the left to open the throttle, speeding up the engine and increasing its power.

The proximity of the air governor to the unloader valves insures quick opening of said valves and the positive pressure of air passing from governor 15 to the throttle control takes care of the matter of slowing the engine. But because of the length of pipes 28 and 24, the engine would lag 55 in starting after the unloader valves have closed.

To avoid such a lag I have inserted a quick release valve at 29, close to the throttle control. Preferably this valve is of the type having a piston held down by the pressure of the air in the system but adapted to rise quickly upon decrease of pressure, and so to open a relatively large port leading back from the wheel chamber, thus releasing the air in the chamber so that the throttle can be opened wide suddenly by the action of spring 21. The control through the governor is too slow to prevent the undesirable racing of the engine, and is also too sluggish in picking up speed when the pressure falls in the tank. Nor would it be satisfactory to place the governor 15 midway between the throttle control and the unloader, as that would slow down the entire operation, whereas by placing the governor close to the unloader and the quick release valve close to the throttle control satisfactory operation of the engine and compressor is had.

It will be obvious to those skilled in the art that many changes may be made in the device herein disclosed, all without departing from the spirit of the invention; and therefore I do not limit myself to what is shown in the drawings and described in the specification, but only as indicated in the appended claim.

Having thus fully described my invention, what I claim is:

In combination: a storage tank for compressed air, an air compressor for supplying air to the tank, unloader valves on said compressor, an

internal combustion engine driving said compressor, a throttle valve for said engine, resilient means operating to advance the throttle valve, pneumatic means mounted on said engine and operable by a pressure increase to retard the throttle valve, an air pressure governor mounted on the compressor, a conduit establishing communication between the governor and the tank, conduits extending from said governor to the unloader valves and to the pneumatic means to unload the compressor and to retard the throttle valve when a predetermined maximum pressure is attained, and a quick release valve interposed in the conduit between the governor and pneumatic means and spaced therebetween, said valve being arranged to open on a fall in air pressure to a predetermined point and cause the quick release of air from the pneumatic means to permit the quick and unopposed action of the resilient means upon the engine throttle.
